US0D1012102S

(12) **United States Design Patent** (10) Patent No.: **US D1,012,102 S**
 Williams et al. (45) Date of Patent: ** Jan. 23, 2024

(54) **DISPLAY SCREEN OR PORTION THEREOF WITH GRAPHICAL USER INTERFACE**

(71) Applicant: **Lingo Sensing Technology Unlimited Company**, Dublin (IE)

(72) Inventors: **Justin N. Williams**, Oakland, CA (US); **Jessica Inchauspé**, New York, NY (US); **Michael Rogers**, Menlo Park, CA (US)

(73) Assignee: **LINGO SENSING TECHNOLOGY UNLIMITED COMPANY**, Dublin (IE)

(**) Term: **15 Years**

(21) Appl. No.: **29/821,557**

(22) Filed: **Dec. 30, 2021**

(51) LOC (14) Cl. **14-04**

(52) U.S. Cl.

USPC **D14/485**

(74) Attorney, Agent, or Firm — McAndrews Held & Malloy, Ltd.

(57) **CLAIM**

The ornamental design for a display screen or portion thereof with graphical user interface, as shown and described.

DESCRIPTION

The patent file contains at least one drawing executed in color. Copies of this patent with color drawings will be provided by the Office upon request and payment of the necessary fee.

The FIGURE is a front view of a display screen or portion thereof with graphical user interface showing our new design.

The outer perimeter illustrated by dashed broken lines in the FIGURE illustrates a display screen or portion thereof and forms no part of the claimed design.
